Toronto 16, Ontario, Canada

Filed Feb. 19, 1965, Ser. No. 83,888

Term of patent 14 years

(Cl. D9—6)

FIGURE 1 is a top plan view of a floor mat or similar article showing my new design, it being understood that the quarter shown is continued throughout the rest of the enclosed area which is partly broken away for convenience of illustration;

I claim:

The ornamental design for a floor mat or similar article, as shown and described.
